UNITED STATES PATENT OFFICE.

GOTTHILF ANSGARIUS BETULANDER, OF SODERTORNS VILLASTAD, SWEDEN, AS-
SIGNOR TO THE RELAY AUTOMATIC TELEPHONE COMPANY, LIMITED, OF LONDON,
ENGLAND.

ELECTRICAL SWITCHING DEVICE.

Application filed August 17, 1921. Serial No. 493,131.

To all whom it may concern:

Be it known that I, GOTTHILF ANSGARIUS BETULANDER, a subject of the King of Sweden, and resident of Sodertorns Villastad, Sweden, have invented a new and useful Improvement in Electrical Switching Devices, of which the following is a specification.

This invention relates to switching devices employed in connection with a system of electrical lines of two orders for connecting any line of the first order of which the electrical condition becomes modified to an idle line of the second order.

According to this invention means are provided whereby whilst the connecting means is dealing with a modified line of the first order, other lines of that order whose condition has been modified subsequently to that line, are disabled from connection but so soon as the connecting means is capable of dealing with these lines they are enabled for connection. The invention is especially applicable to telephone systems and for the sake of clarity it will therefore be described in connection with a plant in which the lines of the first order are lines by which operators at an exchange can transmit orders and which can be connected for this purpose to a line or lines of the second order by known switching devices adapted to distribute the calls in such a way that when a plurality of calls comes in at the same time to the switching section only one calling line can be connected at one time. By this invention a shifting device is combined with the call distributor, which device divides the calls into groups, of which one group comprises such calls as have been switched into readiness for connection as soon as a line of the second order becomes disengaged, whilst another group comprising calls which have come in later than the calls of the first group consists of lines which have not as yet been prepared for connection, the arrangement being such that no call in the second group can be switched into readiness for connection before all the calls in the first group have been dealt with. So soon as

the calls of the first group have been dealt with, however, all the lines of the second group are at once switched into readiness for connection and subsequent calls are prevented from connection until all this second group has been dealt with, and so on.

The sequence in which the calls are dispatched within each group is arbitrary, it is true, but as the group contains a lesser number of calls than the total number of calls occurring at the same time, the aforesaid disadvantage will be materially reduced.

Such grouping of the calling lines is effected in the simplest manner by causing the shifting device, which preferably consists of a relay, to affect the circuits or contacts through which the lines are marked as calling so that new lines cannot be marked as calling, and consequently cannot be connected, before the shifting device has been correspondingly actuated, the latter being then in turn controlled partly by members marking the common lines as engaged, and partly by call relays or the like, in such a manner that the shifting device is not brought into operation until all the common lines have been engaged, and shifting does not take place until all the lines, which have already been marked as calling, have been connected.

The invention is illustrated in the accompanying drawing, in which Figs. 1, 2 and 3 show three different switching arrangements according to the invention.

In the switching arrangement shown in Fig. 1, AL1, AL2, AL3, and AL4 denote four speaking lines, for instance for the exchange of orders between telephone operators, which lines may be connected to a common line GL, through relays MR1, MR2, MR3 and MR4 respectively. To each line AL are allotted a call relay AR1, AR2, AR3, and AR4 and a key K1, K2, K3, and K4 respectively. The shifting device consists of a relay OR. In this case the relays MR also form the call controller, in that the circuits of these relays extend over series connected contacts k1, k2, k3, k4 in all the relays MR so that only one line AL can be connected at a time.

KR is a contact relay co-operating with the call controller.

For example, if an operator at line AL1, desires connection with line GL, she depresses K1 so as to close a circuit through AR1. The latter attracts its armature and connects itself into a circuit 2 through OR. A circuit 3 is closed through MRI which attracts its armature and connects itself into a circuit 4 containing KR. The switching is then completed. The connection established is maintained as long as the key K1 is depressed. If during this time other operators try to obtain connection, for instance over lines AL2 and AL3, by depressing corresponding keys K2 and K3, lines AL2 and AL3 cannot immediately be marked as calling, because the circuit AR2 and AR3 is open at OR. Only when the prevailing connection is open and GL becomes disengaged, can the waiting operators be marked as calling, in that the circuit of OR is then broken at K1, in consequence whereof OR releases its armature and closes circuit 1 for AR2 and AR3. These latter then attract their armatures simultaneously and connect themselves into the circuit 2, OR again attracts its armature and thus prevents subsequent calls from being marked as calling. At the same time AR2 and AR3 close circuit 3 for MR2 and MR3, but relay MR2 immediately after breaks the circuit of MR3, and consequently only MR2 retains its armature attracted, over circuit 4 containing KR which is now again brought into operation. Of the two lines AL2 and AL3 only the former has thus been connected to GL. When the operator, releases K2, circuit 4 of MR2 and KR is broken, whereas the energization of OR is maintained over K3. MR2 and KR release their armatures and then close circuit 3 of MR3 which attracts its armature and connects itself into circuit 4, whereby connection between AL3 and GL is established.

Now, if another operator should have depressed for instance key K4 before line AL3 had obtained its connection, she could not interfere with the call previously marked on line AL3, because OR is still in its operative position. Thus a later call cannot be dispatched before all the lines already marked as calling have been connected. Only on GL becoming disengaged by release of K3, is line AL4 marked as calling, connection being then established as just described.

When calls are very frequent the calls (or lines AL respectively) are in this way divided by OR into two groups, of which one comprises lines already marked as calling, and the other lines which have not as yet been marked as calling. In consequence of the call controller selecting the

calls in the order in which the corresponding relays MR are connected to earth over contacts k1 to k4, it may happen that the connection within each group of lines marked as calling does not take place in the proper sequence, but, as by the said division of the calls the number of lines which may be simultaneously marked as calling, is reduced the disadvantageous effect of the call controller on the sequence of dispatch is considerably reduced.

Fig. 2 shows a suitable embodiment of the switching arrangement when a plurality of common lines is used. The figure shows two such lines GL1 and GL2. In this case the connections are established by means of a known switching device in which the groups of contacts KG through which lines AL are connected to lines GL are arranged in rows at right angles to each other, the said rows corresponding to the various lines AL and GL, the selection and actuation of the group KG, corresponding to the connection in question, being then effected by means of a number of marking relays MR corresponding to the various lines AL, and by a number of connecting relays GR corresponding to the various lines GL, the said connecting relays GR co-operating with one another in such a manner that the connection is established by energizing the relays which correspond to the lines AL and GL in question. The marking relay MR then effects such a marking of the groups KG in the corresponding vertical row that the relay GR, which is adapted to actuate the groups situated in the corresponding horizontal row, only actuates the group situated at the point of intersection between the horizontal and vertical rows in question. Moreover, there is provided in this arrangement a testing device comprising a number of relays PR, by means of which that line GL is selected which for the time being is disengaged, and cut off relays UR are allotted to the different lines AL.

On AL1 calling for instance circuits 1, 2, 3 and 4 are first completed as in Fig. 1 except that circuit 2 extends over contacts KG1 KG2 in relays GR when any one of the lines GL is disengaged. KR then switches in relays PR to the test wires of lines GL, said test wires, if the respective lines are disengaged, being connected to earth at contacts KG3 KG4 in relays GR. If both lines GL are assumed to be disengaged, a circuit 5 is now closed through each of the relays PR1 and PR2 and an operating winding on each of the relays GR, but as PR1 immediately breaks circuit 5 of GR2, only GR1 is brought into operation. A holding circuit 6 is then closed through the holding winding of GR1 and cut-off relay UR1. Thus connection is established over

group KG11. Relay UR1 breaks circuit 4 of MR1 and KR, which release their armatures so as to disconnect relays PR.

Now if a call occurs on AL2 while a previous connection is still maintained, AL2 is connected in like manner to GL2. The short circuit of OR and circuit 2 over OR are then discontinued, the said relay thus only now being brought into operation and preventing subsequent calls from being marked as calling. In case of calls occurring in AL3 and AL4 while both lines GL are still engaged, these calls have no effect until a line GL becomes disengaged. If for instance GL1 first becomes disengaged, OR is first short circuited over contact KG1. On OR releasing its armature, circuits 1 of AR3, and AR4 are closed, the said relays at the same time attracting their armatures and switching themselves into circuits 2. Thus AL3 and AL4 are marked as calling. At the same time circuit 3 and then circuit 4 of MR3 are closed, the connection of AL3 to GL1 taking place in the manner previously described. The short circuit of OR is again discontinued, and the relay attracts its armature, thereby preventing subsequent calls from being marked as calling until AL4 shall have obtained connection. Only on the call on AL4 having been dispatched and a line GL having again become disengaged, may new calls be marked and dispatched.

Fig. 3 shows a modification of the arrangement according to Fig. 2, the lines AL being divided into two sections AL1, AL2, AL3 and AL'1, AL'2, AL'3, in order to avoid too many series connected contacts *k*, in relays MR. These sections as regards the shifting are to be regarded as a single section, in that the marking of waiting lines as calling takes place simultaneously in both sections, but the connection of the lines marked as calling takes place by sections, preference being given to the one section.

In Fig. 3 relay OR is thus common to all lines AL and AL1, and further the testing relays PR are common to both sections. On the other hand, there is a controlling relay KR or KR1 respectively for each section, these relays controlling the circuits of one another so that only one of them can be brought into operation at a time, preference being given to KR, so that if calls are marked at the same time in both sections, calls in the section corresponding to KR are dispatched first, and then calls in the other section. Only after all of the lines marked as calling in both sections have been connected, can shifting take place, to enable later calls to be dispatched. In the example shown, the short circuiting contacts *k*12, *k*21 are arranged in special relays BR, the circuits of which are under the control

of connecting relays GR, so that the same effect is obtained as in Fig. 2. Likewise, contacts *k*1 are arranged in special relays HR which are connected in series with respect to the relays MR. Thus this arrangement does not involve any change in the mode of operation, but has for its object only to attain a more rapid breaking of the contacts *k*1 than may be obtained with relays MR. Lines GL are shown as connected to plugs P1, P2 co-acting with a plug switch K6, so that the line is marked engaged when the corresponding plug is raised. Moreover, lines GL are marked engaged at the moment of connection through relays BR which break contacts K6. With the above-mentioned exceptions, the mode of operation is the same as in Fig. 2, as will be readily understood by a comparison of the figures.

The keys K may obviously be contacts of relays which become operated upon a line AL becoming calling.

I claim—

1. The combination with a system of electrical lines of two orders in which any line of the first order upon its electrical condition becoming modified is enabled for connection to an idle line of the second order and means for effecting the connections, of means whereby whilst the connecting means is dealing with a modified line subsequently modified lines are disabled from controlling the connecting means and whereby such subsequently modified lines are all enabled and maintained in condition for connection and thereafter connected one at a time.

2. The combination with a system of electrical lines of two orders in which any line of the first order upon its electrical condition becoming modified is enabled for connection to an idle line of the second order and means for effecting the connections, of a shifting device adapted to divide lines whose condition has become modified into groups of which one group comprises such of the modified lines as have been switched into readiness for connection, whilst another group comprises lines which have become modified whilst the connecting means is connecting lines of the first group.

3. Arrangement according to claim 2 in which there are means for disabling from connection lines of the second group and means whereby the lines of the second group are simultaneously enabled as soon as all the lines of the first group have been dealt with.

4. Arrangement according to claim 2 in which the shifting device is normally inoperative and in which there are means operative upon all the lines of the second order becoming engaged for bringing the shifting device into operation and means whereby

all lines of the second group are simultaneously enabled for connection as soon as any of the lines of the second order becomes free after the lines of the first group have

5 been dealt with.

5. Arrangement according to claim 2 in which the shifting device consists of a relay adapted to be controlled partly by a device

which engages the lines of the second order and partly by devices actuated when lines 10 of the first order become modified.

In testimony that I claim the foregoing as my invention I have signed my name this 22nd day of July, 1921.

GOTTHILF ANSGARIUS BETULANDER.
